UNITED STATES PATENT OFFICE.

DANIEL SNYDER GUSTIN, OF NEWARK, NEW JERSEY, ASSIGNOR TO WESTINGHOUSE LAMP COMPANY, A CORPORATION OF PENNSYLVANIA.

METHOD OF PRODUCING A HIGH VACUUM IN VESSELS.

Application filed September 6, 1922. Serial No. 586,461.

This invention relates to a method of producing a high vacuum in vessels and more particularly to the evacuation of electric incandescent lamp bulbs, radiotron bulbs and the like.

An object of the invention is to produce a high degree of vacuum in a vessel.

Another object of the invention is to produce a high vacuum by producing a physical change in a gas within a vessel.

A further object of the invention is to create a high vacuum in a vessel in an expeditious, simple and economical manner.

Other objects and advantages will be apparent from the following description.

It is the usual practice to provide a vacuum in a vessel, such as an electric incandescent lamp bulb, by the employment of one or more vacuum pumps. The pumps are designed to produce different degrees of vacuum and successively increase the vacuum until a proper degree is reached. Difficulty is, however, encountered in obtaining the high degree of vacuum necessary for certain devices, particularly radiotron bulbs.

After a bulb has been evacuated to the highest possible degree within the capacity of the pumps, a small amount of residual gas remains in the bulb to the detriment of the subsequent life of the device, and the present invention aims to remove the greater part of this residual gas by displacing it with another gas and finally removing the substituted gas, with the result that a high degree of vacuum is obtained.

To accomplish the above, I may first evacuate a vessel to a suitable degree and then displace any gas remaining therein by a selected gas such, for example, as phosphorus vapor. The substitute gas may be caused to completely displace the residual gas by flushing the vessel therewith, which operation may be repeated until only the substitute gas remains. The substitute gas may, however, be introduced into the vessel by diffusion during the removal of the air from the vessel and, if so, I effect a physical change in the substitute gas to remove it.

The evacuation of vessels for use as electric-incandescent-lamp or radiotron bulbs requires the use of comparatively expensive pumps in order to produce a high vacuum, that is, to reduce the residual gas left in the bulb to an extremely low pressure. It is practically impossible to remove the last

traces of such residual gas by mechanical means, even with the most highly efficient pumps.

My invention provides a method of removing or rendering inactive any residual gas that may be left in a vessel after the vessel has been exhausted by mechanical means, such as the usual vacuum pumps. Since the final removal of the gas is not performed by a pump, it is obvious that less expensive mechanical vacuum-producing apparatus may be employed.

I have found that a high vacuum may be produced by replacing the air normally within a vessel by a given gas and finally removing the gas by passing therethrough a high-tension discharge of electricity to eliminate the gas. Any gas may be used which will conduct such a discharge and undergo a physical change from vapor to a non-volatile solid, with substantially no vapor-tension. Phosphorus vapor has been found to give good results.

A preferred method of practicing my invention is to place a chamber containing phosphorus vapor in communication with an exhaust system adapted to evacuate one or more bulbs or vessels and it has been found that, either by diffusion or otherwise, the phosphorus vapor will replace all the gas in the system in a short period of time, thus, when the vessels have been sealed off, the residual gas, as usually found, will have been replaced by the phosphorus vapor. The vessels may then be subjected to a high-tension electrical discharge. At first, a strong glow will be observed as the discharge passes through the gas; after two or three flashes, however, no glow will be observed, which indicates that there is no longer a conducting medium within the vessel. The action of the high-tension electricity upon the phosphorus is such that a physical change takes place and phosphorus is solidified, in the form of what is believed to be red phosphorus, and is precipitated upon the walls of the vessel, and a high or fine vacuum is thus produced.

The invention will be more clearly understood by reference to the accompanying drawings, in which,

Fig. 1 is a side elevation of a vessel to be exhausted, a vapor chamber and suitable tube connections;

Fig. 2 is a similar view of an evacuated

vessel in position for the passage of a high-tension current; and,

Fig. 3 is a like view of another construction for passing an electrical charge through 5 an evacuated bulb.

An incandescent lamp bulb 4 (Fig. 1) is shown provided with a mount 5. It is obvious, however, that a bulb having other internal structure may be employed as, for 10 example, a radiotron. The bulb 4 is connected, through a contraction or exhaust tube 6 and rubber tubing 7, to a tubing system 8. The bulb may be heated in the usual manner to drive out moisture. The tubing system 15 8 may be of the three-way type, one opening 9 being suitably connected to a pump (not shown), and another opening 10 being connected, by a section of tubing 11, to the mouth of a vessel 12. A valve or stop-cock 13 may be suitably disposed at the mouth of the vessel 12 to regulate the outlet of the contents of the same, and a cock 14 may be provided to open or close the line leading to the pump. The third opening 15 of the 20 tubing system 8 is connected by the tubing 7 to the exhaust tube 6 of the bulb, the opening 15 being provided with a valve 16.

For the purpose of indicating the vacuum in the bulb, tubing system and connections 25 thereto, a vacuum gauge 17 is provided.

As illustrated in Fig. 2, a bulb 4, after being evacuated by the pump and tipped off, is so placed that the greater part of its surface is in close proximity to an electrode in 30 the form of a brush 18, and the leading-in wires of the bulb are preferably connected to a contact member 19. The electrodes 18 and contact member 19 may be connected, through conductors 21 and 22, with a high-tension electrical flow from any suitable generator (not shown).

It will be understood that the electrical discharge passes between the external electrode 18 and an internal electrode, which, 35 in the case of a lamp, consists of certain conducting portions of the mount; for example, the leading-in wires and the filament. By the use of an electrode of the brush type, the discharge acts to widely distribute the particles resulting from the physical change produced in the vapor. If desirable, however, 40 an electrode 23 such as shown in Fig. 3 may be provided. The electrode 23 being of relatively small area, may be placed at the base 45 of the bulb and, when a discharge is passed through the vapor to solidify it, the particles thereof will be concentrated and confined within an area of the bulb equal to the surface of the electrode 23, thus, the position of the solidified matter may be controlled and the deposit restricted to any given portion of the bulb.

In practice, the chamber 12, containing white phosphorus vapor, may be connected 50 by the tubing 11 to the system 8, the open-

ing 9 being then connected to an exhausting apparatus and a vessel 4 being connected, by a suitable exhaust tube, to the opening 15.

Assuming that the valves are all closed, the valves 14 and 16 may then be opened and 55 the vessel exhausted to any suitable degree, depending upon the degree of the ultimate vacuum required. The valve 14 may then be closed and the valve 13 opened which will result in the passage of phosphorous vapor 70 to the vessel by reason of the difference in pressure between the vessel 4 and the chamber 12, the pressure of the vapor being the greater. The valve 13 may then be closed and the valve 14 opened, causing an evacuation 75 of the vapor from the vessel 4. The operation of filling the vessel with vapor may be repeated until all the air that may have remained in the vessel after the mechanical exhaust is displaced by phosphorus vapor. 80 The filling and flushing of the vessel 4 may be repeated any number of times. It has been found, however, that one flushing is sufficient for vacuum-type incandescent electric lamps. 85

It is obvious that, if desirable, the vapor may be generated as needed, in which case, a quantity of phosphorus may be provided in the chamber 12 and heated by any suitable means to vapor form. 90

When the vapor has completely displaced the residual gas in the vessel, the vessel may be tipped or sealed off by the usual fires 95 23, indicated in dotted lines in Fig. 1, and the vessel may then be subjected to a high-tension discharge to effect the physical change in the gas, and a high vacuum will result. In so far as is known, the effect of the electrical discharge through the vapor is to change the white-phosphorous vapor to 100 solid or red phosphorus, the high-tension discharge having caused a change in the character of the gas leaving a substance, which is non-volatile or with substantially no vapor tension at room temperatures, and a fine vacuum is produced with but a relatively small amount of work by mechanical means, such as the pumps. 105

As above described, the phosphorus may be flushed into the vessel 4 but it has also been found that good results are obtained by permitting the vapor to diffuse into the vessel 4. Diffusion is accomplished by opening all the valves and operating the pump to evacuate the system. In a relatively short time 115 the gas within the vessel 4 will be replaced by the phosphorus vapor from the chamber 12 by diffusion. The time required depends on the size of the vessel 4 and other factors and may be readily determined in a given instance by experiment. The vessel may be tipped off and the high-tension discharge 120 passed through the vapor, with the result as above set forth.

The production of a high vacuum by my 130

method has many advantages; for instance, when employing my method in connection with the manufacture of lamps, the flashing operation, as now practiced, may be omitted.

- 6 It is well known that lamps are flashed, to clean-up residual gases, by the activation of a getter, such as magnesium, provided in the form of a small deposit upon a portion of the filament of the lamp, it being then cus-
10 tomary to bring the filament to a state of incandescence to activate the getter to improve the vacuum. The lighting of the lamp, however, changes the structure of the filament and renders it relatively brittle and liable
15 to rupture during transportation or handling incident thereto.

It is evident that, when employing my method, the residual gas is disposed of without the necessity of lighting the filament, 20 and a lamp may, therefore, be shipped to the user with the filament in its original state and thus enable it to better resist jars or impacts during shipment.

While I have shown and described what, 25 at the present time, may be considered a pre-

ferred arrangement for practicing my in-vention, it is to be understood that the same is merely illustrative, and modifications may be made therein which fall within the spirit and scope of the appended claims.

30

What is claimed is:

1. The method of evacuating a vessel which comprises flushing said vessel with a vapor until the vessel contains the said vapor only and passing an electrical discharge be- 35 tween an external electrode and an electrode within said vessel to effect a physical change in said vapor.

2. The method of evacuating a vessel which comprises displacing air normally 40 within said vessel with a vapor, passing an electrical discharge through said vessel to solidify the vapor and in controlling the position of the resultant solid within the vessel.

45

In testimony whereof, I have hereunto subscribed my name this fifth day of September 1922.

DANIEL SNYDER GUSTIN.
